UNITED STATES PATENT OFFICE.

HENRY O. SCHMIDT, OF NEW YORK, N. Y., ASSIGNOR TO SIMONS, BROTHER & CO., OF PHILADELPHIA, PENNSYLVANIA.

DESIGN FOR A CANE OR UMBRELLA HANDLE.

SPECIFICATION forming part of Design No. 19,959, dated July 1, 1890.

Application filed April 15, 1890. Serial No. 348,114. Term of patent 3½ years.

To all whom it may concern:

Be it known that I, HENRY O. SCHMIDT, a citizen of the United States, residing in New York, in the county and State of New York, have invented and produced a new and original Design for Cane or Umbrella Handles, of which the following is a specification, reference being had to the accompanying drawing, forming part thereof.

10 In the drawing is shown a side elevation of an umbrella or cane handle illustrating my new design.

A is the body part, and is slightly rounded in its configuration, being larger at the top 15 and curved over at its upper part to form a rounded shoulder. The body part A is surrounded by a curved cap or head B of plain surface. The body part is ornamented by slightly spiral or oblique grooves C extending 20 around it, and also with ornamentations D E F is the base part, and consists of a large

band curved upon its outer portion and highly ornamented. The base part F is separated 25 from the body part A by an annular band G of plain surface, and is relieved on its lower part by a second annular band H of plain surface.

The body part A is of plain surface and 30 may be relieved by shaded work adjacent to the ornamentations D and E.

The handle is made of any suitable material.

Having now described my new design, what 35 I claim as new, and desire to secure by Letters Patent, is—

The design for umbrella or cane handles, substantially as herein described and shown.

In testimony of which invention I have 40 hereunto set my hand.

HENRY O. SCHMIDT.
